UNITED STATES PATENT OFFICE.

ALFREDO DIATTO, OF TURIN, ITALY.

ELECTRIC RAILWAY.

SPECIFICATION forming part of Letters Patent No. 783,687, dated February 28, 1905.

Application filed November 20, 1902. Serial No. 132,136.

To all whom it may concern:

Be it known that I, ALFREDO DIATTO, a subject of the King of Italy, residing at Turin, in the Kingdom of Italy, have invented certain new and useful Improvements in Electric Railways, of which the following is a full, clear, and exact description.

The invention relates to improvements in magnetic apparatus for the distribution of current to electric tramways and railways by road contact. This class of apparatus has the defect that if a derivation of current is produced between the contact-pavement and the rails when the magnetic interrupter retakes its normal position of rest there is set up between the movable contact and the fixed contact of the interrupter a voltaic arc which impairs the apparatus and may consequently be the cause of accidents.

20 The improvement which forms the subject of the present invention has for its object to obviate the said inconvenience by means of the application of a magnetic extinguisher which has for its object to suddenly extinguish the arc which would have a tendency to be produced by a derivation such as above referred to or from any other cause.

25 The accompanying drawings represent the application of the present invention of magnetic extinguisher to apparatus of my system; but it is evident that such an extinguisher may be applied in an analogous manner to other similar systems.

Figure 1 is a vertical section, the left half drawn on the line 1 2 of Fig. 2, the right half drawn on the line 2 3 of the same figure; and Fig. 2 is a plan of one mode of carrying the invention into effect. Fig. 3 is a vertical section showing a modification.

30 The magnetic extinguisher is constituted by an iron ring *a*, extending by the pieces *b* into the interior of the apparatus and by the wire *f*, which is conveniently wound around the ring *a*. If the wire *f* is traversed by the 35 electric current, *b* will be the poles of a double electromagnet, and the lines of magnetic force going from one pole to the other

across the space traversed by the movable contact of the apparatus will have the faculty of extinguishing the arcs in question. To cause 50 the current to pass into the wire *f*, one of its extremities may be made to communicate with the underground cable *k* and the other with the mercury in the cup *g*; but the arrangement represented at Fig. 3 gives a better insulation and facilitates the setting up of the apparatus by establishing connections at the upper part of the contact-box. These connections are established on two iron disks *h* and *i*, insulated from each other and in communication the one with the fixed contact *e*, the other with the road contact *c*. In this manner the current traverses the windings, the iron ring or electromagnet *a* after contact is established between *d* and *e*, and passes to 65 the road contact *c* through the piece *h*. The pieces *h* and *i* having a very slightly different potential, their insulation from each other presents no difficulty. As soon as the contact ceases between *d* and *e* the current ceases 70 to pass into the windings of the ring or electromagnet *a* unless from any cause an arc is established between the contacts, in which case this arc is immediately extinguished.

Having fully described my invention, what 75 I claim, and desire to secure by Letters Patent, is—

The combination with magnetic interrupters, used in the distribution of current to electric tramways and railways by road contacts, of a magnetic extinguisher consisting of an iron ring surrounding the apparatus, pieces connected to the ring and extending into the interior of the apparatus, a wire wound round the iron ring and electric connections to the ends of said wire, substantially as herein set forth.

In witness whereof I have hereunto set my hand in presence of two witnesses.

ALFREDO DIATTO.
